United States Patent Office

Des. 185,512
Patented June 16, 1959

185,512

PLAQUE

Clarence Hubert Ropp, Lake Bluff, Ill., assignor to F. H. Noble & Company, Chicago, Ill., a corporation of Illinois

Application December 29, 1958, Serial No. 53,965

Term of patent 14 years

(Cl. D29—23)

Fig. 1 is a perspective view of the plaque showing my new design.

Fig. 2 is a vertical sectional view of the plaque as taken along the line 2—2 of Fig. 1.

I claim:

The ornamental design for a plaque, substantially as shown.
